UNITED STATES PATENT OFFICE.

ROSWELL G. HALL, OF DORCHESTER, AND AXEL BIRKHOLM, OF BOSTON, MASSACHUSETTS.

CLEANING-ROD FOR FIREARMS.

1,386,862.

Specification of Letters Patent. Patented Aug. 9, 1921.

Application filed December 15, 1919. Serial No. 345,011.

To all whom it may concern:

Be it known that ROSWELL G. HALL and AXEL BIRKHOLM, citizens of the United States, residing, respectively, at Dorchester, county of Suffolk, and Boston, county of Suffolk, Commonwealth of Massachusetts, have invented certain new and useful Improvements in Cleaning-Rods for Firearms, of which the following is a specification.

10 This invention relates to gun cleaners or similar articles on which a patch, rag or other cleaning fabric is placed for the purposes of running it through a restricted passage such as the bore of a rifle.

15 Our invention therefore is capable of a very wide application and use but for the purposes of the present application we shall limit our discussion of it to its applicability and utility in cleaning rods for firearms as 20 that use so well illustrates the principles involved as to afford ample guidance for its adoption in other usages.

The cleaning of the bore of small arms is obviously a matter of prime importance. 25 For this purpose the most convenient and generally satisfactory method has been to thrust through the bore a patch or small square of fabric in the various steps of cleaning, polishing and oiling.

30 In practice, the patch is placed over the end of a cleaning rod or through an eye at the end of the rod. It is of course highly important that the patch when inserted into the bore on the rod make a snug fit in the 35 bore so as to be forced into the angles of the lands and grooves and generally exert a very considerable degree of friction in its passage back and forth through the barrel in order to remove all fouling.

40 While this method is of a simple nature, it is attended by certain well known possibilities of mishap even in the hands of trained men. It is not always possible to have patches of exactly the right size for 45 the caliber of the piece to be cleaned, and there is also considerable variation in the diameter of the cleaning rods ordinarily available. Furthermore, even if the patches are carefully cut to size for a given caliber 50 of cleaning rod, the element of the thickness of the patch and the degree of symmetry in the placing of the patch on the end of rod, are factors which go to make up variations in the tightness of the fit of the cleaner in 55 the bore.

The result of all this are apparently unavoidable instances in which the patch after being entered in the bore is found to be entirely too tight and to require an undue thrust from the end of the rod. This has 60 the immediate tendency to punch a hole through the fabric allowing the rod to pass through the patch. When this occurs a very annoying situation is almost certain to follow, as the patch freed from the rod then 65 becomes jammed and the more pressure it is subjected to the worse the jam becomes.

In an effort to relieve the pressure at the end of the rod it has been customary for 70 generations to groove the rod adjacent the head in order to get a grip on the patch along the sides of the rod. Such groovings have afforded some help, but it has never been sufficient to overcome the difficulties hereinbefore recited. The difficulty now 75 appears to have been due to the fact that such groovings either would not give a well defined radial face or if given such face offered such faces in only one direction so that upon reversal of the motion of the rod 80 the patch was left free. Furthermore, it is to be noted that any groove cut about the cleaning rod has a tendency to weaken it with a risk of breaking off the end of the rod under some sudden strain.

85 By our invention we have overcome all of the above difficulties and through a perfectly simple treatment of the end of the rod have provided a gripping surface which engages the patch laterally in both directions of longitudinal movement with a maximum gripping effect and with a minimum of weakening of the end of the rod. This 90 we accomplish in short by an alternation and reversal in a series of notches, the principle of which we will now describe.

95 For the purposes of illustration we have selected a form which we have found well adapted in use, especially with small calibers. In the drawings illustrating this 100 form:

Figure I is a side view of a rod end.

Fig. II a side view of the rod end turned ninety degrees.

Figs. III, IV and V are cross sections, 105 and Fig. VI is an end view.

We have indicated in the drawings merely the end portion of a cleaning rod 1. The remainder of the rod may be of any conventional form. Usually a rounded or cy- 110

lindrical rod is used which for smaller calibers of rifle bores is of composition brass of sufficiently small diameter to fit freely within the bore with a slight amount of 5 clearance on all sides.

We prepare the end of such a rod by first reducing it adjacent to the extreme end to a form angular in cross section. In the instance shown, the rod is squared leaving 10 a short cylindrical knob 10 at the extreme tip of the rod. In forming this squared portion we therefore obtain four longitudinally disposed edges, 2, 3, 4, and 5 of ninety degree angle. The squared portion 15 preferably tapers slightly forward so that the planes of the lateral faces so formed are tipped slightly in toward the longitudinal axis of the rod.

We then cut in the edges of the squared 20 portion a series of notches N. Each notch is defined by one face *a* in a plane vertical to the longitudinal axis of the rod and another face *b* intersecting the base of the face *a*, inclining to said longitudinal axis 25 at a convenient angle.

In the form shown, each one of these faces will be triangular. The apex of the face *a* will be pointed outwardly and in conjunction with the apex angle of the face *b* of 30 the next succeeding notch defining an intermediate tooth T.

The notching of the edges 2, 3, 4, and 5 is reversed alternately so that the notches on the edges 2 and 4 are faced in one direction and the notches in the edges 3 and 5 are faced in the opposite direction. Furthermore, the notches of the alternate edges are staggered so that the notches on the edges 2 and 4 and those formed on the edges 35 3 and 5 come relatively intermediate of each other. This prevents a continuous weakening in the cross section of the rod on any given transverse plane.

When viewed on the angle as appears in 45 Fig. I, it will be seen that the rod has a zigzag face of substantial area running its entire length. When viewed on the angle as appears in Fig. II, a continuous series of serrations appear. By reference to the development shown in Fig. III, it will be seen that these serrations alternate in their disposition in adjacent rows so that in progressing around alternate rows of teeth are encountered in successive reversals of disposition.

While we have described the specific form shown in considerable detail, it is not to be understood as in any way limiting ourselves either to the number of longitudinal faces 60 and angles formed or in the number or nature of the notches cut, nor in the character or shape of the teeth formed between such notches. It will be understood that a great variety of facetings may be secured 65 by changing the number of longitudinal

facings and the shape and number of the notches.

The form shown, however, is characteristic in the results obtained. The area adjacent the end of the rod will be found to 70 have a high degree of gripping action on the inclosing patch between it and the wall of the bore. In the first place, the patch is held by plural longitudinal facings. Second, the patch is engaged by facets disposed 75 in both directions of rotative tendency, and third, due to the inclination of longitudinal facings, a radial grip is effected through the lodging of the folds of the patch back of the cylindrical head 10.

The rod may be given various additional features, some of which although well known in cleaning rods have advantageous combination with the engaging surface hereinbefore described. It may be noted that 85 the rod may be adapted for any given arm by facing off the gripping section so as to give a number of longitudinal corners or ridges corresponding to the number of lands in the particular bore. Furthermore, by 90 proportioning and spacing the teeth and arranging the stagger in alternate rows, the teeth may be brought into spiral rows corresponding to the pitch of the rifling in the 95 specific piece.

Modifications such as above suggested, as well as many others which would naturally occur in meeting modified requirements or circumstances of use, may all be freely resorted to as within the purview of our invention if within the limits of the appended 100 claims.

What we therefore claim and desire to secure by Letters Patent is:

1. A cleaning rod of the class described 105 having an end portion of rectangular cross section defined on two sides by a pair of opposite faces disposed in planes converging in one direction and having oppositely disposed notches cut in the longitudinal edges thereof.

2. A cleaning rod of the class described 110 having an end portion of rectangular cross section defined on two sides by a pair of opposite faces disposed in planes converging in one direction and having oppositely disposed notches cut in the longitudinal edges thereof, and on two other sides by a pair of opposite faces disposed in planes converging in the opposite direction and having oppositely disposed notches cut in the 115 longitudinal edges thereof.

In testimony whereof we affix our signatures in presence of two witnesses.

ROSWELL G. HALL.
AXEL BIRKHOLM.
